CONTAINER

George Arlington Moore, Louisville, Ky., assignor
to Humoco Corporation, Louisville, Ky., a cor-
poration of Delaware

Application January 30, 1936, Serial No. 61,477

6 Claims. (Cl. 229—44)

This invention relates to containers and more particularly to fabricated containers and parts thereof, and to the art of deforming fibrous or similar materials to impress desired contours or shapes of a permanent nature therein such as, for example, the deformation of single sheets, or laminated blanks of such materials, to form said containers or parts thereof.

It has been heretofore proposed to provide means for deforming blanks of fibrous materials to form containers and other irregularly shaped articles by means of cooperating die members, but the deformed portions of the resulting articles have had an inherent tendency to spring back toward the original shape of the blank when the article is removed from the die unless the internal structure of the material is broken down at the bending line. In practice, it is very advantageous to either reduce or wholly prevent the tendency of a shaped blank to assume its original form and, accordingly, one of the objects of the present invention is to provide a novel means and method for rendering deformations of paper, fiberboard and like materials substantially permanent.

Another object of the present invention is to provide a novel cover for a container body which is adapted to be secured thereto in a novel manner.

Another object of the invention is to provide a light, yet sturdy, container which may be readily manufactured in large numbers and at low cost, either in small or large sizes.

Still another object is to provide a novel container constituted by two or more parts, one of which is a hinged cover drawn from a single blank that may, if desired, be latched in position for closing the container by cooperating deformations on said cover and the container body.

A further object is to provide a container including one or a plurality of novel portions formed of fibrous and acetate sheet laminations.

A still further object is to provide a container comprising fibrous materials and having an end closure of similar materials secured thereon in a novel manner.

Another object is to provide a novel method of fabricating a container for diversified utility.

The above and further objects and novel features of the invention will more fully appear from the following detailed description when taken in connection with the accompanying drawing. It is to be expressly understood, however, that the drawing is designed for the purpose of illustration only and not as a definition of the limits of

the invention, reference for this latter purpose being had primarily to the appended claims.

In the drawing, wherein like reference characters refer to like parts throughout the several views.

Fig. 1 is an isometric view of one form of container embodying the present invention;

Fig. 2 is a vertical section of the container of Fig. 1, the section being taken on line 2—2;

Fig. 3 is a rear elevation of the container of Fig. 1;

Fig. 4 is a section similar to Fig. 2 showing another embodiment of the invention; and,

Fig. 5 is a partial sectional view on an enlarged scale of a third embodiment of the invention.

As illustrated by way of example in Figs. 1 to 3, inclusive, the novel container comprises a rectangular body 10, having rounded corners, and a novel cover 11 therefor, each made from a single blank of material, said blanks being drawn and formed into desired complementary shapes and associated with one another in a novel manner to be hereinafter described.

For the purpose of counteracting the common tendencies of resiliency, warpage, and other stresses to return deformed fibrous material to its original form and to insure the permanence of the deformations in the blanks when the same are drawn to proper shapes for forming body 10 and cover 11, said blanks are constituted by a novel laminated structure comprising fibrous and acetate laminae, the latter of which may be rendered semi-plastic by the application of heat. The acetate lamina preferably forms the outer surface of the blanks and, in addition to assisting in rendering the deformations therein permanent in a manner to appear hereafter, renders the container moisture resistant, toughens the same without destroying the flexibility thereof, and gives a pleasing appearance to the same. In the form shown, the blank from which body 10 is formed is composed of a single sheet 10a, (Fig. 2) of fibrous material, such as fiberboard, having a thin sheet 10b of cellulose acetate intimately secured to the outer surface thereof by means of an intermediate bonding stratum preferably consisting of a solvent adhesive. A very thin cellulose acetate lacquer is satisfactory for this purpose, the solvents therein being effective to render the acetate material tacky and the solids thereof serving as a binding medium for the fibrous materials. This lacquer is not activated by heat of ordinary temperatures, such as room temperature. One solvent adhesive which has been found suitable contains about 20% solids

including some resins and a plasticizer. If desired, acetate sheet 10b may be colored, to prevent the appearance of the adhesive film therethrough, by adding thereto a proper pigment of 5 any suitable color.

Blank 10a, 10b, having been first cut to the proper shape for forming container body 10, is preferably subjected to a drawing operation whereby an inwardly projecting rib 12 is formed 10 around the central portion thereof. The peripheral outline of said rib is preferably the same shape as the container and is provided for the purpose of giving a degree of rigidity and additional strength to the base of body 10, whereby 15 excessive bowing or warpage of the same is prevented. Rib 12 may be drawn in blank 10a, 10b by cooperating male and female dies of suitable configurations substantially in the manner disclosed in my Reissue Patent No. 19,504, issued 20 March 19, 1935.

By the operation of the same die members employed in forming rib 12, the marginal portion of blank 10a, 10b is drawn into flanged relation with the central portion thereof to form the 25 vertical side walls of container body 10. A light, yet sturdy, body having seamless side walls which are integral with its base is thus formed.

For a purpose to appear hereinafter, a pair of grooves 13 and 14 are formed in the back wall 30 of body 10, the former and larger of the two being impressed adjacent the bottom and the latter adjacent the upper edge of said body. Grooves 13 and 14, each of which is parallel to the top and bottom of body 10, preferably comprise a 35 horizontal ledge portion *a* extending inwardly at right angles to the vertical side walls, an intermediate portion *b* which is substantially parallel to the side walls, and an inclined portion *c* connecting the side wall and said intermediate portion and disposed at an angle of substantially 45° thereto. Said grooves as shown extend substantially across the uncurved portion of the back wall of body 10. A similar groove or groove 40 15 is also drawn in the front wall of said body to constitute a part of latching means for cover 11 to be hereinafter described.

A novel cover is provided for body 10 which is made from a single blank of material and adapted to be secured to said body in a novel 50 manner whereby the same may be pivoted at a predetermined bending line thereon for opening and closing the container. In the embodiment illustrated, cover 11 is drawn from a laminated blank constituted by an inner sheet of fibrous 55 material 11a and an arcuate sheet 11b secured to one another in the same manner as the laminations of blank 10a, 10b. An inwardly projecting rib 16 is drawn about the central portion 60 of blank 11a, 11b and the marginal portion thereof is drawn into flanged relation with said central portion in the same manner and by the same means employed in the formation of body 10 as above described. The dimensions of said cover and body are such that the same will have a 65 close telescopic fit, the latter being adapted to fit within the flanged portion of the former.

In order to facilitate the deformation of the blanks by the drawing and forming dies in the process of making body 10 and cover 11 and for 70 the purpose of rendering said deformations permanent, the dies are preferably heated in any suitable manner such as by electricity or steam. Heat conducted to the blanks from the dies is effective to render the fibrous materials more 75 pliable and thus more susceptible to deformation

without buckling or wrinkling. The heat also renders the acetate sheets 10b and 11b plastic, thereby permitting the deformation thereof without setting up stresses in the internal structure of the same, and without danger of destroying 5 the bond between the acetate and fiber laminae. Upon the removal of the formed articles from the heated dies, the acetate sheets set quickly in deformed position when allowed to cool and, being free from stresses, are effective to hold the 10 deformed fiberboard under stress and against any tendencies of the same to spring back toward its original position. If desired, the blanks may be deformed by heated dies and then deposited into cold transfer dies, whereby said acetate 15 lamina is cooled and permitted to set prior to the removal of the formed article.

In order that cover 11 may be secured to body 10 and move freely in hinged relation thereto, the rear vertical wall thereof has portions cut 20 away adjacent the corners, as best seen in Fig. 3, said rear wall then constituting a skirt or tab 17. The latter is provided with a pair of grooves having inwardly projecting complementary ribs 13a and 14a which register with grooves 13 and 25 14, respectively, in body 10 when the cover is in position. Rib 13a constitutes means for anchoring cover 11 to prevent its being sheared from body 10, while rib 14a which is shown inverted constitutes a bending line or hinging point for 30 said cover, the horizontal ledge *a* being effective to absorb the thrust when the cover is pivoted to open position. The front and end flanges of cover 11 are adapted to firmly engage the corresponding walls of body 10. 35

Cover 11, as shown, is secured to body 10 by a suitable adhesive interposed between the rear wall of body 10 and tab 17. In the process of fabricating the container, a thin dry coating of thermoplastic adhesive, adapted to be activated 40 by heat, a solvent, or both, is preferably applied to the inner surface of tab 17. Said adhesive film may be activated by a suitable solvent applied to the rear wall of body 10 just prior to pressing the cover in place on said body. Tab 17 is preferably pressed against body 10 by means of a suitably shaped heated iron, the heat being effective to further activate the adhesive and to assist in conforming the deformed tab to the contour of the grooved wall of said body, and the pressure 45 acts to force the activated adhesive into the interstices of the adjacent fiber and acetate sheets, thereby substantially welding the same together.

In order to releasably secure cover 11 in closed position on the container body in such a manner 55 as to provide against accidental opening thereof, latching means are provided by drawing an inwardly projecting rib 15a in the front flange of said cover, which is adapted to register with groove 15 in the face of body 10. The material 60 employed in making the cover has sufficient resiliency to cause rib 15a to spring into said groove and be resiliently held therein when the same are in registering position. As shown, the edges 18 created by cutting away a portion of 65 the flange at each end of the rear wall of cover 11, as above pointed out, may be in the planes of the end walls of body 10, thus permitting said cover to be pivoted at line 14a without interference. Preferably, however, edges 18 extend a 70 short distance around the rounded corner of body 10, as shown in Fig. 3, for the purpose of assisting latch 15, 15a in holding cover 11 in closed position. The distance which said edges may thus extend around the back of body 10 will be 75

determined by the resiliency and toughness of the material employed in making cover 11.

A portion of the front flange of cover 11 may be cut away as at 19 and lugs 19a and 19b may be provided on body 10 and cover 11, respectively, to permit the parts to be gripped by the operator while pivoting the cover to open position. Cover 11 is shown in a partially open position by dotted lines in Fig. 2.

10 Due to the compacting of material which results from drawing an annular flange in a blank, there is a definite limit to the depth or length of flange which can be drawn if a smooth flange surface is desired. Accordingly, there is a limit 15 to the depth of the container shown in Figs. 1 to 3, inclusive. The invention, however, is not limited to containers of a specific depth or height, and a second embodiment of the invention is illustrated in Fig. 4 wherein a body portion 20, 20 corresponding to body 10, and a removable cover 21, are joined by a spacer 22 of fibrous material, such as paper, to form a container of greater depth. As shown, spacer 22 is telescopically received by flanged body member 20 and secured 25 thereto by means of an adhesive 23 adapted to be activated by heat, a solvent, or both. A thin, dry coating of thermoplastic adhesive is preferably applied to the outer, marginal surface of spacer 22 and activated after member 20 is in 30 place by heat conducted from dies adapted to press against both sides of the joint. The pressure of the dies is effective to distribute the heat activated adhesive and press the same into the interstices of the fibrous materials, thus substantially welding member 20 in place and forming an impervious joint between the same and spacer 22. Said spacer may be regarded as the container body and member 20 as an end closure therefor.

40 The upper end of spacer or body 22 is telescopically received by cover 21 which may be similar in construction to cover 11 or, if desired, may be removably mounted on said body. As shown, said cover is provided with a continuous 45 peripheral flange 24 having inwardly directed ribs 25, similar to rib 15a, at opposite sides of the cover, said ribs being adapted to cooperate with correspondingly shaped grooves 26 in body 22 for yieldingly latching the cover in place. Preferably, the central portion of spacer 22 is 50 enlarged so that the outer surface thereof is flush with the outer walls of member 20 and cover 21, thus providing a smooth surface for the reception of a label. It will be understood, however, that body 22 may be printed before forming, thus avoiding the necessity for a label.

55 Another embodiment of the invention is shown in Fig. 5 wherein spacer 22 is replaced by a liner 29 to which member 20 and, in the form shown, a pivoted cover 27 similar to cover 11 are secured in the same manner in which said member and cover 11 are secured to their respective container bodies, as above described. The tab at the rear of cover 27 is provided with only one rib 28 which constitutes a bending line for cover 27, said tab being secured to body 29 by an adhesive 30. Body or liner 29, as shown, is just long enough so that when it is telescopically fitted into parts 20 and 27, the edges of said parts will abut and the outer surfaces thereof will be flush with one another.

60 In the enlarged view (Fig. 5), there is illustrated a covering 31 of cellophane or other suitable material which may be secured over the top of liner 29 after the container has been filled and

before cover 27 is secured thereto. A similar secondary covering may be used in the embodiments of Figs. 1 and 4, if desired, the same being secured directly to body 10 in the embodiment of Fig. 1. It will be noted that the container of Fig. 5 may be fabricated to have a depth equal to twice the length of the maximum length of flange which can be safely and smoothly drawn in a blank. The container of Fig. 4, however, is not limited as to depth.

10 There is thus provided a container which is fabricated from novel laminated blanks which are drawn and formed into cooperating elements, one of which is a novel cover, said cover being so constructed that it may be removably latched on the container body or secured to the same for pivotal movement relative thereto and releasably latched in closing position by cooperation with a deformation in the wall of the container body. A refillable container is also thus provided which 20 is light and inexpensive yet durable in use and which has a pleasing appearance. If desired, the inner surfaces of the container body and closures may be coated with a dry film of nitro-cellulose lacquer to render said surfaces impervious.

25 It is to be expressly understood that the invention is not limited to the embodiments illustrated and described but that various changes may be made, such as in the size and shape of the container illustrated and the specific materials 30 specified, without departing from the spirit and scope of the invention, the blanks employed having outlines or configurations to suit the desired deformations, size and shape. For a definition of the limits of the invention, reference will be 35 had primarily to the appended claims.

What is claimed is:

1. A container comprising a body constituted by a blank of fibrous and acetate sheet laminations joined by a bonding stratum of solvent adhesive, said blank having the marginal portion thereof drawn into flanged relation with the central portion thereof, and a cover for said body constituted by a blank of fibrous and acetate sheet laminations, said last-named blank comprising a central portion, a flange portion, and a skirt constituting hinge means, said skirt having a rib thereon adapted to cooperate with a groove in the wall of said body and being adhesively secured to the latter, and said flange portion and the flange of said body having cooperating deformations therein constituting latching means for releasably holding the cover in closed position on the body.

2. A container comprising a body constituted by a blank having the marginal portion drawn into flanged relation with the central portion thereof, and a cover for said body constituted by a blank having the marginal portion drawn into flanged relation with the central portion thereof, parts 60 of said last-named marginal portion being cut away to provide a tab whereby said cover may be adhesively secured to said body for pivotal movement thereon.

3. A container comprising a body constituted by a member comprising a central portion and a seamless peripheral flange, and a cover for said body constituted by a member comprising a central portion, a tab at one side for adhesively securing the cover to the body and constituting 70 hinge means for the cover, and a flange portion at the other sides adapted to engage said peripheral flange.

4. A container comprising a body constituted by a member comprising a central portion and a 75

- seamless peripheral flange, and a cover for said body constituted by a member comprising a central portion, a skirt at one side for adhesively securing the cover to the body and constituting hinge means for the cover, and a flange portion, the latter and said peripheral flange having cooperating deformations therein constituting latching means for releasably holding said cover in closed position on the body.
5. In a container, a body constituted by a member comprising fibrous materials and having a marginal portion thereof drawn into a seamless peripheral flange, and a cover for said body constituted by a member comprising fibrous materials and having a marginal portion drawn into

flanged relation with the central portion thereof, said peripheral flange and last-named marginal portion having cooperating deformations therein to yieldingly hold said cover in closed position on the body.

5

6. In a container comprising fibrous materials, a body having a plurality of straight side walls, the latter having deformations therein, and a cover for the body having straight walls adapted to engage the straight walls of the body and ribs 10 in the walls of said cover for stiffening the same, said ribs being adapted to cooperate with said deformations to hold the cover in position on the body.

GEORGE ARLINGTON MOORE.
